UNITED STATES PATENT OFFICE.

GEORGE A. LONG, OF HARTFORD, CONNECTICUT, ASSIGNOR TO THE GRAY TELEPHONE PAY STATION COMPANY, OF HARTFORD, CONNECTICUT, A CORPORATION OF CONNECTICUT.

TELEPHONE PAY-STATION.

1,101,130.

Specification of Letters Patent. Patented June 23, 1914.

Application filed August 6, 1913. Serial No. 783,255.

To all whom it may concern:

Be it known that I, GEORGE A. LONG, a citizen of the United States, residing at Hartford, in the county of Hartford and 5 State of Connecticut, have invented certain new and useful Improvements in Telephone Pay-Stations, of which the following is a specification.

This invention relates to telephone pay-stations, one of the primary purposes of the invention being to provide simple and effective means by which a prepay telephone-pay-station can be quickly and easily converted into a postpay one.

15 In the drawings accompanying and forming part of the present specification I have shown in detail one of the several convenient forms of embodiment of the invention, which to enable those skilled in the art to 20 practise the same will be set forth fully in the following description. I do not restrict myself to this showing; I may depart therefrom in several respects within the scope of the invention defined by the claim following said description.

25 Referring to said drawings: Figure 1 is a sectional rear elevation of the hopper, discharge chutes, and certain coöperating devices of a prepay telephone-pay station 30 equipped with the locking-means involving my invention. Fig. 2 is a top plan view of the magnet, its armature and certain coacting elements including the locking-member. Fig. 3 is a detail view in perspective of said 35 locking-member.

Like characters refer to like parts throughout the several figures.

At the present time there are in general use two types of telephone-pay stations, one 40 wherein the subscriber inserts into the machine the money in payment of the toll after he gets his "party" and the other wherein the toll is paid before the connection is obtained. As will be inferred those of the 45 first kind are known as "postpay" while the other are termed "prepay". These postpay machines have been employed for a great number of years whereas the prepay machines have only come into use at a comparatively recent date. There are occasions 50 where it becomes necessary to change a prepay machine into a postpay one and at the present time to accomplish this it is essential to remove the greater part of the equipment thereof and substitute therefor equip-

ment of a radically different character. I provide means whereby all this is avoided.

A prepay machine comprises a plurality of discharge-chutes and means for directing at will or otherwise, a coin or coins along 60 either of these chutes. One of these chutes is adapted to direct the coin or coins into a money box within the station while the other is adapted to deliver the coin or coins outside the station or exteriorly of the casing 65 or housing thereof. An example of a prepay station is shown in Letters Patent No. 917,742 granted to me April 6, 1909. In conjunction with the coin-directing means of whatever character the same may be, is 70 locking-means which is of such nature as to hold the coin-directing means in one of its two shifted positions, in the present instance in such relation that the coin or coins will be delivered into the money box or like compartment within the machine. These several parts may be of any suitable nature.

With the foregoing general description it is now in order to refer to the organization illustrated in the drawings.

80 In Fig. 1 the numeral 1 may denote a base member which is suitably rigidly mounted in the casing of the telephone pay station and which sustains the polarized electromagnet 2 coöperative with the poles 3 of 85 which is the oscillatory armature 4. Depending from said oscillatory or rocking armature at its center of movement, is the arm 5 terminating at its lower end in the fork 6 straddling the pin 7 projecting laterally from the flap 8 mounted for swinging movement in the hopper structure 9 the two discharge chutes 10 and 11 leading from said 90 hopper structure, the chute 10 to direct the coin or coins into the coin box or equivalent receptacle while the chute 11 conducts the coins to a point outside the casing of the station where they can be reached by the subscriber. When the magnet 2 is deenergized its armature stands in a neutral position, the pendent arm 5 at this time being substantially vertically disposed, the flap or coin-director being also approximately vertical so that the anti-friction roller or analogous part 12 at the upper edge of said flap 95 will be under the temporary coin-supporting part 13 pivoted within the hopper structure 9. It will be supposed that there are one or more coins resting on the pivoted support 100 13, and that the flap 8 is standing vertically. 110

If current of one polarity be sent through the magnet 2 the armature 4 thereof will be attracted in such manner as to swing, through the arm 5, the flap 8 in a direction 5 to release the support 13 and hence the coins resting thereon and cause the gravitation of the coins into the chute 10 and hence into the coin-box. If current of opposite polarity be sent through the magnet, the support 13 10 will be released but the flap will be swung to cause the coins to enter the chute 11 by which they will be returned to the subscriber.

The foregoing is a general and comparatively brief description of the machine shown in the Letters Patent to which I have alluded.

It will be clear that if the flap 8 be locked in the position it is shown as occupying in 20 Fig. 1, the coins will pass into the chute 10 and from the latter into the coin box or receptacle, and as will be understood from what has already been stated, such means may differ decidedly as to character. In 25 like manner it is not essential that I employ any particular kind of prepay machine.

In Fig. 3 I illustrate in detail a locking member 14, which answers my requirements and in Fig. 1 this locking member is shown 30 as occupying its effective position. It is shown as bifurcated to straddle one of the poles of the magnet 2, the pole on the right in Fig. 1 being shown as thus straddled, the deeper leg of the said locking member being 35 in engagement with the body of the armature 4 so that the armature being locked against motion it follows that the flap or equivalent coin director 8 cannot be operated notwithstanding the fact that the magnet 40 be energized or some similar act performed. To maintain the locking member 14 in operative position any suitable means,

such as the holding pin 15, may be utilized, this pin preferably being in the form of a screw, to prevent its accidental displacement 45 the deeper leg or branch of the bifurcated locking member having a tapped hole to receive the threaded portion of the screw 15 while the other leg has a plain hole to receive the screw. It will be assumed that it is 50 desired to lock the flap 8 in position to make a postpay out of a prepay instrument. In this event the screw 15 is taken from place, if it be in place, after which, the armature 4 is swung over, by hand, to the position it is 55 shown as occupying in Fig. 1, when the locking member 14 is passed over its appropriate pole 3. The screw 15 is then put into place.

In conclusion I should state that at the 60 present time when there is occasion to change a prepay telephone pay station into a postpay one, it is required that the base 1 with all the parts supported thereby, be dismounted and an entirely different base with 65 entirely different equipment put in its stead. By virtue of the improvement I eliminate all this trouble and all the additional expense of keeping double equipment.

What I claim is:

In a telephone pay station, a plurality of chutes, means involving a polarized electro-magnet and its armature, for directing coins in desired order into said chutes, and a forked locking member removably straddling 70 one of the poles of said magnet, for locking said armature against movement.

In testimony whereof I affix my signature in presence of two witnesses.

GEORGE A. LONG.
